UNITED STATES PATENT OFFICE.

ROBERT L. BOYD, OF NEW YORK, N. Y.

SELF-BINDING BLOTTER.

SPECIFICATION forming part of Letters Patent No. 529,892, dated November 27, 1894.

Application filed August 9, 1893. Serial No. 482,787. (No model.)

To all whom it may concern:

Be it known that I, ROBERT L. BOYD, a citizen of the United States, and a resident of New York, county and State of New York, have 5 invented a certain Self-Binding Blotter, of which the following is a specification.

My invention relates to blotting pads and in particular to an appliance whereby the sheets of blotting paper may be engaged with 10 and detached from the same at will, and it has for its object the provision of a device, neat and ornamental in appearance, simple and inexpensive in construction, and efficient in practical use.

15 To attain the desired end my invention consists in the construction and arrangement of parts first shown and described and then pointed out in the claims.

In the drawings which form a part of this 20 specification Figure 1, represents a plan or top view of my blotter. Fig. 2, is a view of the back or under side of the same. Fig. 3, is a section on the line 3, 3, Fig. 1. Fig. 4, is a view in section, and Fig. 5, a plan view of 25 other blotters constructed according to my invention.

Like letters of reference indicate like parts in all the views.

Referring again to the drawings, A, denotes 30 a sheet of transparent or translucent material, as of celluloid, constituting a face for, and ordinarily secured, as by means of fastening devices a , to a suitable supporting body, frame or backing, as the preferably 35 flexible card board sheet or tablet B. At ordinarily one end of the supporting sheet B, I provide the said fasteners a , with a holding or engaging device, as an offset formed by washers a^2, a^3 , Fig. 3, constituting practically 40 a flange extending from the shank of the fastener a ; or consisting of a head a^4 , Fig. 4, located at the extremity of the shank extending from the shoulder a' , of the fastener a . An equivalent engaging means is denoted by the 45 eyelets a^5 , Fig. 5. The sheets of the blotting paper C, are also provided, preferably at one extremity of the same, with engaging devices, as the orifices or recesses C^3 , constructed and arranged to become interlocked with the holding 50 means with which the back B, is provided. In the present instance by simply bending the

blotter C, the recesses C^3 , may be inserted in the holding devices a^3 , or a^4 , and the parts will be held in normal position by means of the inherent stiffness or spring of the blotting paper—my appliance thus constituting a self binding blotting pad. If preferred, the end of the blotter C may be folded over as represented in Figs. 1, 2 and 3, in order that the bottom or lower face of my appliance, or blotter proper may present a neat and symmetrical appearance. 55

After being used for a period, the blotter C, may be detached from the supporting back B, and inserted in the same again in a reversed 60 position or, if preferred, a new sheet of blotting paper may be engaged with the said supporting back. 65

Other suitable rigid or movable holding devices may be substituted for those shown and 70 described.

It is manifest that the sheet B, may be suitably ornamented, and also that the transparent or translucent material A, may be dispensed with if so desired. 75

It is evident that many slight changes in the construction and relative arrangement of parts may be resorted to without departing from the spirit and scope of my invention.

What I claim as new, and desire to secure 80 by Letters Patent, is—

1. A self binding flexible blotting pad consisting of a supporting back and translucent face secured together by engaging means consisting of perpendicular pins provided with 85 heads, in combination with a sheet of resilient blotting paper also provided with engaging means consisting of recesses formed in the sides of the same, and constructed and arranged to be sprung into lateral interlocking 90 engagement with and detached from the said support at will, and to be retained in said normal position solely by means of the resilience of the edges of said lateral recesses.

2. A self binding flexible blotting pad consisting of a supporting back provided with engaging means consisting of perpendicular pins provided with heads, in combination with a sheet of resilient blotting paper, longer than the said back, one end of which paper is constructed and arranged to be folded over upon itself, and is provided with engaging means 95 100

consisting of recesses formed in the sides of the same and constructed and arranged to be sprung into lateral interlocking engagement with and detached from the said support at 5 will, and to be retained in said normal position solely by means of the resilience of the edges of said lateral recesses; the faces of the blotting paper and supporting back being made to mutually conform.

In testimony of the foregoing specification I do hereby sign the same, in the city of New York, county and State of New York, this 24th day of March, A. D. 1893.

ROBERT L. BOYD.
